UNITED STATES PATENT OFFICE.

FRED WAITE, OF OTLEY, NEAR LEEDS, ENGLAND.

INK-SAVING DEVICE FOR INTAGLIO PRINTING AND EMBOSSED PRESSES.

1,351,545.

Specification of Letters Patent. Patented Aug. 31, 1920.

Application filed February 11, 1920. Serial No. 357,992.

To all whom it may concern:

Be it known that I, FRED WAITE, a subject of the King of Great Britain, residing at Otley, near Leeds, in the county of York, England, have invented certain new and useful Improvements in Ink-Saving Devices for Intaglio Printing and Embossing Presses, of which the following is a specification.

In intaglio printing and embossing presses, the wiping-paper has been scraped with a view to effecting a saving in ink by causing a scraper to bear direct on the large paper-carrying cylinder, but the unyielding resistance behind the scraper causes the paper to tear if surface inequalities occur. In another known construction where no solid resistance is provided, the clean side of the paper passes two rollers and a scraper projects slightly into the path between the said two rollers; but as in certain machines the tension behind the scraper varies considerably, owing say to the tension being relaxed so much at the start of the feed forward that the paper is quite slack, the paper is not cleaned anything like so uniformly and efficiently as when the paper is kept under tension.

Now this present invention has for its object the provision of an ink-saving device of the scraper type, the arrangement being such as to cause the paper when traveling over the scraper to be always kept taut irrespective of the tension of the paper behind, thus insuring the recovery of the maximum quantity of ink.

According to my invention, the device consists of a scraper blade situated at one side of the paper and being adapted to project into a narrow groove or recess formed in a member situated at the opposite side of the paper, the depth of the scraper blade within the narrow groove or recess of the oppositely situated member and the width of the groove or recess being such as to cause the paper to be bent at an angle so as to keep the contact between the scraper blade and the paper practically uniform irrespective of the tension of the paper behind; in other words, the entry and leaving contact edges of the narrow groove or recess are situated sufficiently below the engaging edge of the inserted scraper blade as to cause the paper to be bent within the said narrow groove or recess to such an angle as to insure it being always kept taut while traveling over the said scraper blade.

A form of construction consists in mounting the scraper blade across the machine at the underside of the traveling paper in fixed end bearings and in carrying the 60 grooved or recessed member across the machine at the opposite or top side of the traveling paper in pivotally mounted end bearings provided with an operating handle by which latter the said grooved or recessed 65 member is free to be rocked backward on its pivot away from the scraper blade for facilitating the threading of the web of paper or of being rocked forward on its pivot toward and over the scraper blade 70 into the normal or paper-engaging position, the grooved or recessed member being elastically held in the normal or paper-engaging position over the scraper blade by means of a tension spring and being locked 75 in the out of operation position by a pawl, while the scraper blade may be so held in its carrying-bearings as to dispense with the use of screws or the like fixing means and a suitably positioned screw may be provided for regulating the depth to which the scraper blade is caused to enter the narrow groove or recess of the pivoted member.

An alternative form of construction consists in pivotally mounting the scraper 85 blade and stationarily mounting the grooved or recessed member, the scraper blade in this case being rocked backward on its pivot away from the grooved member for facilitating the threading of the web 90 of paper and forward on its pivot toward the grooved member to bring it into the normal or paper-engaging position in a similar manner to that of the construction previously described where the scraper blade 95 is fixed and the grooved member pivoted.

In order that the invention may be clearly understood, I will proceed to describe the same with reference to the example of construction shown in the accompanying drawings; wherein:

Figures 1 and 2 are respectively a side elevation and an end elevation of a portion of an intaglio printing and embossing press having its wiper-paper fitted with an ink-saving device constructed in accordance with my invention; and Fig. 3 is a sectional side elevation of the same ink-saving device, drawn to an enlarged scale.

Referring to the drawings, the side frames 110 1 of the press are provided with fixed end bearings 2 carrying a scraper blade 3 which

extends across the machine at the underside of the traveling paper 4 immediately in advance of the large paper-carrying cylinder 5, while at the opposite or top side of the traveling paper 4 the side frames 1 of the press carry a rock-shaft 6 provided with end bearings 7 carrying a member 8 which extends across the machine and is formed with a longitudinal narrow groove or recess 9 for the entry thereinto of the oppositely situated scraper blade 3. One of the end bearings 7 which carry the grooved member 8 is formed with an operating handle 10, through the medium of which latter the said grooved member 8 is free to be rocked backward on its pivot 6 away from the scraper blade 3 into the position shown in full lines at Fig. 1 for facilitating the threading of the wiper-paper 4 or of being rocked forward on its pivot 6 toward and over the said scraper blade 3 into the normal or paper-engaging position shown in dotted lines at Fig. 1 and in full lines at Fig. 3.

When the parts are in the paper-engaging position shown at Fig. 3, the depth of the scraper blade 3 within the narrow groove or recess 9 of the oppositely situated member 8 and the width of the said narrow groove or recess 9 are such as to cause the paper 4 to be bent at a sharp angle into the narrow groove so as to keep the contact between the scraper blade 3 and the paper 4 practically uniform irrespective of the tension of the paper behind; in other words, the entry and leaving contact edges of the narrow groove or recess 9 of the member 8 are situated sufficiently below the engaging edge of the inserted scraper blade 3 as to cause the paper 4 to be bent within the said narrow groove or recess 9 to such an angle as to insure it being always kept taut while traveling over the said scraper blade 3.

The pivoted member 8 is elastically held in the normal or paper-engaging position over the scraper blade 3 by means of a tension spring 11 attached to an arm 12 fixed on the rock shaft 6, and the operating handle 10 is provided with a pivoted pawl 13 adapted to engage a notch 14 in one of the side frames 1 for locking the pivoted member 8 in the out of operation position against the action of the tension spring 11 (see Figs. 1 and 2). The end carrying-bearings 2 are each provided with a slot hole 15 (see Fig. 3) for the reception of the scraper blade 3 which is thus positioned within the said end bearings 2, and each end bearing 2 is pro-

vided with a set screw 16 (see Fig. 3) adapted to bear against the underside of the pivoted member 8 for regulating the depth to which the scraper blade 3 shall enter the narrow groove or recess 9 of the said pivoted member 8.

A removably mounted tray 17 is provided beneath the scraper blade 3 for receiving the scraped off ink and conducting it outwardly from the machine.

What I claim as my invention and desire to secure by Letters Patent is:

1. In ink saving devices of the scraper type for the recovery of ink from the wiping paper of intaglio printing and embossing presses; the combination with a scraper blade situated across the machine at one side of the paper, of a member situated across the machine at the opposite side of the paper and being formed with a longitudinal narrow groove or recess into which the scraper blade projects, and means for adjusting the position of the scraper blade to regulate the depth thereof in the groove or recess of the said member to cause the paper to be bent at an angle to an extent sufficient to keep the contact between the scraper blade and the paper practically uniform irrespective of the tension of the paper behind.

2. In ink saving devices of the scraper type for the recovery of ink from the wiping paper of intaglio printing and embossing presses; the combination with a stationary scraper blade situated across the machine at one side of the paper, of a member pivotally mounted across the machine at the opposite side of the paper so as to enable it to be rocked backward on its pivot away from the stationary blade for facilitating the threading of the web of paper and being formed with a longitudinal narrow groove or recess into which the scraper blade normally projects, and a set screw adjustment for regulating the position of the scraper blade to determine the depth thereof in the groove or recess of the said member to cause the paper to be bent at an angle to an extent sufficient to keep the contact between the scraper blade and the paper practically uniform irrespective of the tension of the paper behind.

In witness whereof I have hereunto set my hand in the presence of two witnesses.

FRED WAITE.
